W. W. JACKSON

GRAIN DOOR TABLE CLAMP

Filed June 6, 1922

INVENTOR

William W. Jackson,
By John Howard McElo
HIS ATTY.

UNITED STATES PATENT OFFICE.

WILLIAM W. JACKSON, OF OAKDALE, LOUISIANA, ASSIGNOR TO MUMMERT LUMBER & TIE COMPANY, OF CHICAGO, ILLINOIS, A CORPORATION OF ILLINOIS.

GRAIN-DOOR TABLE CLAMP.

Application filed June 6, 1922. Serial No. 566,431.

To all whom it may concern:

Be it known that I, WILLIAM W. JACKSON, a citizen of the United States, and a resident of Oakdale, in the parish of Allen and State 5 of Louisiana, have invented certain new and useful Improvements in Grain-Door Table Clamps, of which the following is a specification.

My invention is concerned with grain-10 door table clamps, and is designed to produce a clamping device of the class described in which the operators at each end of the table, by depressing their respective treadles, can produce a powerful horizontal 15 thrust on the surface of the table to hold the boards tightly together while the battens are being nailed on, thus insuring that the completed door shall be perfectly tight.

To illustrate my invention, I annex here-20 to a sheet of drawings, in which the same reference characters are used to designate identical parts in all the figures, of which,—

Fig. 1 is a perspective view of a table embodying my invention, with the parts in 25 their non-clamping position;

Fig. 2 is an end elevation of the same with the treadles depressed to operate the clamp; and

Fig. 3 is a plan view in section on the line 30 3—3 of Fig. 2.

In carrying out my invention, I employ the customary table 10 having the four legs 11 and the working top surface 12, which is preferably covered with metal, and has on 35 the front side thereof the clamping rail 13 and on one end the transverse abutment 14 against which the ends of the boards 15, indicated in dotted lines in Fig. 1, are placed. The mechanism thus far described 40 is of a customary construction and need not be explained in greater detail.

Pivoted at both ends of the table on the pins 16, or other suitable bearings, are the levers 17, partially of a bell-crank shape, as 45 shown, and having the upturned ends 18 of the load arm, to which ends are rigidly secured the longitudinal bar 19, which normally stands away from the adjacent edge of the table a few degrees. Hinged on the 50 bar 19 by the hinges 20 is the movable clamping rail 21, which is preferably constructed of wood, and will have its outer edge parallel with the adjacent edge of the rail 13. The rail is a quadrilateral in cross 55 section, preferably with its under side 22

cut at such an angle to the other three sides, which are at right angles to each other, that when the parts are in the operative position shown in Fig. 1, the bottom 22 of the rail rests flat on the adjacent surface 12. At 60 each end of the table, upon the pin 23, I fulcrum the treadle 24, which is a lever of the second class, and has pivoted thereto at 65 25 a link 26, which is connected to the joint 27 of a toggle composed of the bar 28 pivoted to the frame at 29 at one end, and of the thrust bar 30, the other end of which is pivoted at 31 to the bottom of the power arm of the lever 17. The parts 26, 28 and 30, as well as the lever 17, are preferably composed 70 of flat metal bars, suitably shaped, and I preferably employ a pair of the bars 30 at each end, one on each side of the lever 17, and the bars 26 and 28, in order to secure additional rigidity. I preferably secure on 75 the legs of the table at each end the guard rails 32, between which and the adjacent leg the treadle 24 reciprocates, and to normally hold and return the parts to the inoperative position shown in Fig. 1, I secure at each end 80 a helically-coiled contractile spring 33, one end of which is conveniently secured to the rod 32 while the other end is hooked into an aperture in the lever 17, as shown.

The operation of the complete device is 85 as follows: Assuming that the boards 15 have been placed on the surface 12 with their ends abutting against the member 14, then the operator at each end steps on his treadle 24, depressing it substantially to the position 90 shown in Fig. 2, and during its movement, the powerful leverage exerted by the connections slides the movable rail 21 toward the stationary rail 13 with a powerful thrust and squeezes the boards 15 tightly against 95 each other, in which position they are held by the depressed treadles until the battens have been nailed on, after which the treadles are released and the door can be removed.

While I have shown and described my in- 100 vention as embodied in the form which I at present consider best adapted to carry out its purposes, it will be understood that it is capable of modifications, and that I do not desire to be limited in the interpretation of 105 the following claims except as may be necessitated by the state of the prior art.

What I claim as new, and desire to secure by Letters Patent of the United States, is:

1. In a device of the class described, the 110

combination with a table having a stationary clamping abutment at the top of one side, of a horizontally movable abutment on the top of the other side, a vertically extending lever fulcrumed to each end of the table, said abutment being connected at its ends to the upper ends of the two levers, a treadle lever fulcrumed to each end of the table, a pair of toggle links at each end pivoted at 10 one end to the lower end of the vertical lever and at the other end to the frame, and a link at each end connected at its upper end to the toggle joint and at its lower end to the treadle lever.

15 2. In a device of the class described, the combination with a table having a stationary clamping abutment at the top of one side, of a horizontally movable abutment on the top of the other side, a vertically extending lever fulcrumed to each end of the table, said abutment being connected at its ends to the upper ends of the two levers, a treadle lever fulcrumed to each end of the table, a pair of toggle links at each end pivoted at 20 one end to the lower end of the vertical lever and at the other end to the frame, and a link at each end connected at its upper end to the toggle joint and at its lower end to the treadle lever, and a helically-coiled contractile spring connected at one end to one of the vertical levers and at the other end to the frame.

25 3. In a device of the class described, the

combination with a table having a stationary clamping abutment at the top of one side, 35 of a horizontally movable abutment on the top of the other side, a vertically extending lever fulcrumed toward the rear of the table, said abutment being connected to the upper end of the lever, a treadle lever fulcrumed 40 at the bottom of the table, a pair of toggle links pivoted at one end to the lower end of the vertical lever and at the other end to the front of the frame, and a link connected at its upper end to the toggle joint 45 and at its lower end to the treadle lever.

4. In a device of the class described, the combination with a table having a stationary clamping abutment at the top of one side, of a horizontally movable abutment on the 50 top of the other side, a parallel bar to which said movable abutment is hinged, a vertically extending lever fulcrumed to each end of the table, said bar being connected at its ends to the upper ends of the two levers, a 55 treadle lever fulcrumed to each end of the table, a pair of toggle links at each end pivoted at one end to the lower end of the vertical lever and at the other end to the frame, and a link at each end connected at 60 its upper end to the toggle joint and at its lower end to the treadle lever.

In witness whereof, I have hereunto set my hand this 26th day of May, 1922.

WILLIAM W. JACKSON.
